Primary Examiner — Thomas Johannes*Assistant Examiner* — Shawn T Gingrich(74) *Attorney, Agent, or Firm* — Kammer Browning PLLC(57) **CLAIM**

The ornamental design for a component stand kit, as shown and described.

DESCRIPTION

FIG. 1 is a perspective view of a component stand kit showing my new design, in an environment of use;

FIG. 2 is a perspective view of the core component and the peripheral component of the component stand kit shown in FIG. 1;

FIG. 3 is a front elevational view thereof;

FIG. 4 is a rear elevational view thereof;

FIG. 5 is a first side elevational view thereof;

FIG. 6 is a second side elevational view thereof;

FIG. 7 is a top plan view thereof; and,

FIG. 8 is a bottom plan view.

The broken line portion of the figure drawings is included to show unclaimed subject matter only and forms no part of the claimed design.
